UNITED STATES PATENT OFFICE.

AUGUST N. E. BOOS, OF NEW YORK, N. Y.

ADDING, RECORDING, AND PRINTING MACHINE FOR SERVICE-CHECKS.

1,233,546.

Specification of Letters Patent.

Patented July 17, 1917.

Application filed July 27, 1916. Serial No. 111,567.

To all whom it may concern:

Be it known that I, AUGUST N. E. Boos, a citizen of the German Empire, and resident of the borough of Manhattan, in the 5 city and State of New York, have invented certain new and useful Improvements in Adding, Recording, and Printing Machines for Service-Checks, of which the following is a specification.

10 The present invention relates to improvements in adding, recording and printing machines for service checks, and particularly such a machine for use in restaurants, stores and the like, where it is desirable to have an itemized list of the purchases, the 15 total thereof, and to enable a record of such total and provide a receipt for the customers or guests. An object of the invention is to provide such a machine which will be simple to operate, accurate, and of inexpensive 20 construction.

With these and other objects in view, my invention is shown in the accompanying drawings, and will be hereinafter more 25 fully described with reference thereto, and finally pointed out in the claims.

In the accompanying drawings;

Figure 1 is a perspective view of my improved machine,

30 Fig. 2 is a view of the blank check,

Fig. 3 is a similar view showing the total stamped on the check, and the check perforated,

Fig. 4 shows the same with the receipt 35 portion severed along the line of perforation,

Fig. 5 is a vertical sectional view of the machine,

Fig. 6 shows in detail a toothed rod employed therein,

Fig. 7 is a vertical transverse sectional view along the line 7—7 of Fig. 5,

Fig. 8 is a horizontal sectional view,

45 Figs. 9 and 10 are transverse vertical sectional views similar to Fig. 7, but to an enlarged scale, and showing the operation of the printing lever,

Fig. 11 is a transverse vertical sectional view along the line 11—11 of Fig. 5,

50 Fig. 12 is a sectional view of the indicating wheels and the shafts operating the same,

Fig. 13 is a similar view of the printing wheels,

Fig. 14 is a detail sectional view of one 55 of the printing wheels,

Fig. 15 shows in perspective, one of the spacing means employed,

Figs. 16, 17, 18, 19, 20 and 21 are detail 60 views of the inking roller.

Fig. 22 is a detail view showing one of the supporting members for the inking roll,

Fig. 23 is a detail view showing the other 65 of the supporting members,

Fig. 24 is a detail perspective view showing the perforator,

Figs. 25 and 26 are detail views showing 70 the perforating members,

Fig. 27 shows the feeding mechanism and 75 roll for the recording type,

Fig. 28 is a sectional view of the tape roll,

Fig. 29 shows the tape winding roll,

Fig. 30 is a side view of the supporting 80 standard therefor,

Figs. 31, 32, 33, 34 and 35 are detail views 75 of the tape winding roll,

Fig. 36 is a sectional view of the registering handles,

Fig. 37 shows in detail the locking members, 80

Figs. 38 and 39 are end and side views 85 respectively of the printing operating handle,

Fig. 40 shows in detail the locking member therefor,

Fig. 41 is a front view of the spring,

Fig. 42 shows one side with the cover plate removed, and

Fig. 43 shows the other side thereof, provided with a gear wheel and engaged by the 90 sliding rack.

Similar reference characters indicate corresponding parts throughout the several figures of the drawings.

Referring to the drawings, and more particularly to Fig. 1 thereof, my invention exteriorly comprises a casing 50, having a curved front portion provided with a plurality of slots 51, having increasing amounts indicated at the sides thereof in 100 spaced relation. Levers 52 having handles 53 extend through the slots 51, and are adapted to be moved downwardly therein, opposite the amounts to be recorded. A lever 54 extending through a recess 55 at 105 one side of the casing, and provided with a handle 56 is adapted to be depressed to print and record the amount. The handle

56 may be locked against movement by a lock 56^a. A cushioning block of rubber 54^a is provided at the base of the recessed portion 55, upon which the lever engages upon 5 being depressed.

At the opposite side of the casing a swinging table 57 is provided upon which the check is placed when being totaled, the levers 52 being moved opposite the proper 10 amounts when the total is ascertained. A spring 58 on the table serves to retain the check in place. The amount of the total is indicated at the opening 59 of the portion 60 of the casing, and at the same time printing mechanism contained in the portion 61 of the casing is brought into printing position. A shelf 62 is provided in the casing, and extending outwardly therefrom, above which a perforating device is arranged in 15 20 the casing 63, a drawer 64 being provided beneath the shelf to catch the waste paper. The shelf is mounted upon spring rods 62^a and 62^b disposed in brackets 62^c (Figs. 9 and 10), so that the same is made resilient, 25 thereby taking up any shock caused during the printing and perforating operation. The check, after being totaled, is placed upon the shelf 62, being properly positioned by the flange 65 and the spring fingers 66. 30 The lever 54 is then depressed, causing the check shown in Fig. 2 to be printed in two places, and perforated as shown in Fig. 3. The upper portion may then be severed along the line of perforation as shown in 35 Fig. 4, as a receipt for the customer or guest. The portion 61 is provided respectively above and below the shelf with doors 67 and 68, which may be locked by locks 67^a and 68^a, and which permit access to the printing members and the recording roll 69, upon 40 which the totals are printed as hereinafter more fully pointed out.

The levers 52 are pivoted to a movable frame 70 at 71 Fig. 7, and move between 45 a plurality of arcuate guide members 72, disposed between the upper portion of the frame and a bar 73 supported by the forwardly extending portions 74 of the frame. The under surfaces of the arcuate guide 50 members are provided with a plurality of notches 75, which are adapted to be engaged by a spring actuated tooth 76, controlled by a push button 77 at the end of the handle 53. This is shown in detail in Figs. 55 36 and 37, the tooth being carried at the end of a rod 78 extending upwardly through a socket 79 in the handle, in which is disposed a spring 80 beneath the push button. By pressing downward thereon, it 60 will be seen the tooth is disengaged from the notches of the arcuate guides. The tooth moves in a slot 81 in the lever.

At the rear of the frame 70, and at each side thereof, there are provided rods 82 and 83, which are slidable upon stationary sup-

porting rods 84 and 85, being guided thereon by a socket member 86 at the bottom, and a bearing member 87.

Rack teeth 88 are provided on the rods 82 and 83, which mesh with gear wheels 89, as 70 shown in detail in Fig. 43, mounted loosely upon a shaft 90 provided upon the stationary standards 91 and 92.

Spring drums 93 are secured to the gears 89, and a spiral spring 94 is disposed between the drum and the shaft 90, and the shaft is held stationary by pawls 96, carried on the standards, and which permit tensioning of the spring as desired. Upon moving the frame downwardly, as hereinafter more 75 fully pointed out, the spring is tensioned and upon release of the frame serves to return it to its initial position. Shock-absorbers or bumpers 97 are provided on the supports 84 and 85, which are engaged by the 80 upper ends of the rods 82 and 83 upon this upward return movement, to enable such movement to take place noiselessly and without shock to the machine.

The levers 52 are provided with and operate segmental gears 98 which engage gears 99 mounted respectively upon a plurality of tubular shafts 100, 101, 102, 103 and 104, rotatably mounted in the frame 70, and terminating in a plurality of printing disks 95 105, said disks being disposed in the portion 61 of the casing, and supported by an extension 106 of the frame 70. The telescoping shafts are enlarged interiorly at their ends and engage the entire surface of the 100 next adjacent shaft, so that the greater portion of the shafts are spaced from each other, thereby greatly reducing the frictional contact and permitting easy turning thereof. Each of the disks 105 is provided 105 with a gear 107, and these are connected by racks 108, with corresponding gears of two more sets of printing disks 109 and 110, also mounted in the extension 106 of the frame 70, so that upon movement of the printing 110 disks 105, through the depression of the lever 52, and the corresponding movement of the gears 99, the printing disks 109 and 110 are simultaneously and correspondingly moved. The racks are held in engagement 115 with the gears by grooved rollers 111, supported between posts 112, 113, 114, and 115 of the frame, and held in spaced relation by sleeves 111^a (see Fig. 15). The printing 120 disks 105 and 109 are adapted to print upon the check in two places, while the printing disks 110 print upon a recording tape as hereinafter more fully pointed out. Each 125 of the sets of printing disks is provided with inking means shown in detail in Figs. 14 to 23, and comprise a roller 116 of any suitable material, disposed upon a pintle 117 provided at each end with gears 118 and 119, which are held against rotation with respect to the roller by a wire 120 passing 130

therethrough. The posts are held in place by a washer 121 and a removable cotter pin 122. The roller is supported beneath the printing disks and in engagement therewith by rotatable plates 123 and 124, provided upon the shaft 125 of the disks. Stationary plates 126 and 127 secured to the frame at 128 and 129 are disposed upon the shaft 125 between the plates, rotatable supporting plates and the printing disks, and are provided with teeth 130 which engage the gears 118 and 119 respectively. The plates 123 and 124 are connected by arms 131 and 132 to a stationary frame 133, secured to the upper partition plate 134, the upper ends of the arms engaging a shaft 135 of said frame 133. Upon movement downward of the printing disks, it will be seen, the arms 131 and 132 cause the inking roller to move away from the lowermost type, and at the same time the roller is turned by movement of the gears 118 and 119 with respect to the stationary plates 130 and 131. This position is clearly shown in Fig. 10.

The frame 70 is provided at each side with upwardly extending standards 136 and 137, having a shaft 138 journaled at these upper ends, and upon which are mounted a plurality of gears 139 in vertical alinement with the gears 99, and each provided respectively with tubular shafts 140, 141, 142, 143 and 144, superimposed upon each other. At the ends of the said tubular shafts, there are provided indicating disks 145, having numerals on their periphery which appear at the opening 59 of the portion 60 of the casing, to indicate the type which are brought into printing position. The gears 139 are connected to and move simultaneously with the gears 99 by means of rods 146, shown in detail in Fig. 6, and which are provided at the ends with rack portions 147 and 148 which engage the respective gears. These rods are held into engagement with the gears by means of grooved rollers 149 mounted upon shafts 150, being supported between brackets 152 and 153 provided on the upstanding portions 136 and 137 of the frame.

A perforating device (shown in detail in Figs. 24 to 26, which are perspective views), is carried by the extension 106 of the frame 70, and comprises a cross bar 154 secured to the frame by bracket pieces 155 and 157, and a plurality of perforating rods 158, mounted in the frame by means of their reduced upper ends 159. The lower ends of the perforating rods pass through a bar upon descent of the frame, to pass through holes 161 in the shelf 62, between which and the bar 160 the check to be printed and perforated is placed, thereby causing the same to be perforated.

At the rear of the casing 50, there is provided a frame 162, pivotally mounted upon a shaft 163, supported in standards 164 and 165, which are connected by frame work 166 with the supporting standards 91 and 92 of the spring drums 93, thereby forming the same in one piece and facilitating the manufacture and assembling. The stationary rods 84 and 85 are also secured to this frame work by screws 167, as clearly shown in Figs. 8 and 11. The frame 162 is reinforced and made rigid by a ring 168 secured therein, and the forward ends 169 and 170 are connected to a rod 171 secured between the portions 82 and 83 of the frame 70. The end of the lever 54 is connected to the shaft 163 and is secured to the frame 162 by screws 172 and 173. Upon depression of the lever 54 therefore, the frame 162 is moved downwardly, and the frame 70 is moved downwardly causing the withdrawal of the inking rollers, the type to print and the perforator to perforate the check as above pointed out.

The handle 56 of the lever 54 is provided with a locking device, shown in detail in Figs. 39 to 40, and comprises a slide rod 174 disposed between the lever and the handle, provided at one end with a thumb engaging portion 175, and at the other end with a projecting portion 176, extending through a slot 177 in the lever, and pressed outwardly by a spring 178. The rod is provided with a slot which permits its movement on the handle. The projecting portion engages the arcuate edge 179 of the recessed portion 55 of the casing, the said edge being provided with a notch 180, into which the portion 177 drops at the upper position of the lever. When the same is to be depressed, the rod 174 is pressed inwardly by the thumb, disengaging the portion 177 from the notch and permitting downward movement of the lever.

The recording tape mechanism which is shown in detail in Figs. 27 to 35, is disposed beneath the shelf 62, and comprises a shaft 181 mounted between the plate 134 and a support 182, and upon which a roll of tape 183 is placed. This shaft may be readily removed, when desired for replacing the roll, by removal of a pin 184. A lever 185 provided with a weighted roller 186 bears down upon the roll of tape and prevents its becoming loosened. The paper is carried over rollers 187 and 188, and through slots 189 and 190 beneath the printing disks 110, the end being secured to a roller 191, mounted between standards 192 and 193. This roll is provided with a removable paper attaching rod 194, which fits into a groove 195 in the roll and is provided with a plurality of prongs 196 which extend into sockets 197 of the roll, and which prongs pass through the paper. A recess 198 is provided in the roll, in which is disposed a spring pressed pawl 199, adapted to engage the lever 185.

gage an oppositely disposed and stationary pawl 200, carried by the rod 194, so that upon pressing this rod into the groove of the roll, the same becomes locked therein and may only be removed by insertion of a pin 201 into engagement with the spring pressed pawl.

The end of the roll which engages the standard 192 is reduced as at 202 and is 10 removably held in place thereon by a pin 203, while the other end is provided with a socket 204 and two projecting prongs 205 and 206. The socket 204 is engaged by a shaft 207 upon which is provided a ratchet 15 wheel 208, and the prongs engage a flange 209 on the shaft so that the roll will positively turn with the ratchet. Upon the end of the shaft 207 there is provided a slotted arm 210, provided with a pawl 211 which 20 engages the ratchet. A pawl 212 carried by the standard 193 prevents backward movement of the ratchet. A slide piece 213 is disposed in the slotted arm and is connected 25 by a frame 214, with a roll 215 disposed above the roll 191, and which is lifted as the paper is wound upon the roll 191, thereby causing the slide piece to lift. A spring 216 disposed between the slide piece and a pin 217 provided on the standard 193 serves 30 to hold the roll 215 in engagement with the paper. The slide piece 213 is connected by a rod 218 with a bell crank lever 219, mounted in a bracket 220, and the nose 221 of the lever is engaged in a recess 222 of an arm 35 223 carried by the rod 82, and movable with the frame 70.

As the frame 70 is moved downwardly by depression of the lever 54, the rod 218 is pulled forwardly, together with the arm 40 110, the pawl 211 riding over the ratchet. Upon upward movement of the frame, the projecting lower end 224 of the arm 223 engages the nose of the lever, forcing the rod 218 to its original position and turning the 45 ratchet and paper roll by the pawl 211. This paper is thereby fed forwardly and a new surface is presented for the next printing operation. As the radius of the roll of paper increases, the slide piece 213 is moved 50 accordingly so that the paper is always fed an equal distance.

If desired, the machine may be locked by a lock 225 shown in Fig. 11.

With my improved device, a convenient 55 and accurate recording of the sales may be made, and at the same time the check may be printed twice with the total and perforated, to permit severing of the receipt portion. The machine is positive in action, 60 and requires very little attention, except renewal of the recording tape and inking roller.

I have illustrated and described a preferred and satisfactory form of my inven-

tion, but it is obvious that changes may be 65 made therein within the spirit and scope thereof, as defined in the appended claims.

I claim:

1. In a printing and recording machine of the character described, a stationary supporting frame, a slidable frame mounted to slide with respect to said stationary frame, a swinging frame pivoted at one end and engaging said slidable frame at the other end, a lever arm adapted to swing said 75 swinging frame, movement of said swinging frame adapted to impart a vertically reciprocatory movement to said slidable frame, printing rolls carried by the said slidable frame, and means carried by said 80 movable frame adapted to turn said printing rolls.

2. In a printing and recording machine of the character described, a stationary frame, a slidable frame mounted to slide 85 with respect to said stationary frame, a swinging frame pivoted at one end, and engaging said slidable frame at the other end, a lever arm carried by said swinging frame, movement of said swinging frame adapted 90 to impart a vertically reciprocatory movement to said slidable frame, printing rolls carried by said slidable frame, a plurality of segmental gears mounted in said slidable frame, and adapted to turn said printing 95 rolls, levers carried by said segmental gears extending exterior of said slidable frame.

3. In a printing and recording machine of the character described, a stationary frame, a slidable frame mounted to slide 100 with respect to said stationary frame, a swinging frame pivoted at one end, and engaging said slidable frame at the other end, a lever arm adapted to swing said swinging frame, movement of said swinging frame adapted 105 to impart a vertically reciprocatory movement to said slidable frame, and spring means adapted to be tensioned upon the downward movement of said slidable frame, and adapted to return said slidable frame 110 and said swinging frame to their upward positions upon release, printing rolls carried by said slidable frame, and levers carried by said slidable frame adapted to turn 115 said printing rolls.

4. In a printing and recording machine adapted to print and perforate checks, a stationary frame, a slidable frame mounted to slide with respect to said stationary frame, pivoted means, a swinging lever adapted to impart vertically reciprocatory movement to said slidable frame, a printing table, printing rolls carried by said slidable frame adapted to be brought into engagement with said printing table upon downward movement of said slidable frame, perforating means carried by said slidable frame and adapted to cooperate with said table to 120 125

perforate a check held upon said table, and levers carried by said slidable frame adapted to turn said printing rolls.

5. In a printing and recording machine of the character described, a stationary frame, a slidable frame, a swinging lever adapted to impart vertically reciprocatory movement to said slidable frame, printing rolls carried by said slidable frame, levers carried by said slidable frame, adapted to turn said printing rolls, indicating rolls carried by said slidable frame, means disposed between said indicating rolls and said printing rolls adapted to transmit corresponding movement from said printing rolls to said indicating rolls.

6. In a printing and recording machine of the character described, a stationary frame, a movable frame slidably mounted upon said stationary frame, and adapted to have vertically reciprocatory movement therein and means for depressing said movable frame, printing rolls carried by said movable frame, telescoping shafts respectively connected at one end to said printing rolls, and at the other end provided with gears, and levers carried by said movable frame provided with segments engaging said gears and adapted to turn said printing rolls.

7. In a printing and recording machine of the character described, a stationary frame, a movable frame slidably mounted upon said stationary frame, and adapted to have vertically reciprocatory movement therein and pivoted means for depressing said movable frame, printing rolls carried by said movable frame, levers carried by said movable frame adapted to turn said printing rolls, and inking means engaging said printing rolls, at the printing position in the upper position of said movable frame, and means connecting said inking means to said stationary frame adapted to move said inking means away from said printing position during the downward movement of said movable frame.

8. In a printing and recording machine of the character described, a stationary frame, a movable frame slidably mounted upon said stationary frame, and adapted to have vertically reciprocatory movement therein and pivoted means for depressing said movable frame, a plurality of sets of printing rolls, carried by said movable frame, levers carried by said movable frame adapted to turn one set of said movable rolls, means connecting said rolls to cause corresponding movement of all the rolls by the movement of one, and a recording mechanism disposed beneath one of said sets of rolls, adapted to receive the impression from said rolls, and means adapted to intermittently move said recording mechanism by

the downward movement of said movable frame.

9. In a printing and recording machine of the character described, a stationary frame, a movable frame slidably mounted upon said stationary frame, and adapted to have vertically reciprocatory movement therein, pivoted means for depressing said movable frame, printing rolls carried by said movable frame, levers carried by said movable frame adapted to turn said printing rolls, spring drums mounted on said stationary frame, provided with gears, racks on said movable frame engaging said gears, said spring drums adapted to be tensioned upon downward movement of said movable frame, to return said movable frame to its upper position upon release of said depressing means.

10. In a printing and recording machine of the character described, a stationary frame, a slidable frame, mounted to slide with respect to said stationary frame, a swinging frame pivoted at one end and engaging said slidable frame at the other end, a lever arm adapted to swing the said swinging frame, movement of said swinging frame adapted to impart a vertically reciprocatory movement to said slidable frame, printing rolls carried by said slidable frame, levers carried by said slidable frame adapted to turn said printing rolls, spring means adapted to be tensioned upon downward movement of said slidable frame, and adapted to turn said slidable frame and said swinging frame to their upper positions, and spring buffers on said stationary frame adapted to engage said slidable frame to absorb the shock on return of said slidable frame to its upper position.

11. In a printing and recording machine of the character described, a vertically movable frame, a stationary frame, and means for depressing said movable frame, printing rolls carried by said movable frame, telescoping shafts respectively connected at one end to said printing rolls, and at the other end provided with gears, said shafts being provided interiorly at their ends with enlarged portions engaging the surface of the next adjacent shaft and spaced from the said next adjacent shaft intermediate the said enlarged ends, and levers carried by said movable frame provided with segments engaging said gears and adapted to turn said printing rolls.

12. In a printing and recording machine of the character described, a vertically movable frame, a stationary frame, and means for depressing said movable frame, printing rolls carried by said movable frame, telescoping shafts respectively connected at one end to said printing rolls, and at the other end provided with gears, said shafts being

provided interiorly at their ends with enlarged portions engaging the surface of the next adjacent shaft and spaced from the said next adjacent shaft intermediate the said 5 enlarged ends, levers carried by said movable frame provided with segments engaging said gears and adapted to turn said printing rolls, and telescoping shafts provided at one end with indicating means and 10 at the other end with gears, said shafts being provided at their ends interiorly with enlarged portions and engaging the surface of the next adjacent shaft, and spaced from the next adjacent shaft intermediate the said 15 enlarged ends, and racks connecting said gears of the last-mentioned telescoping shafts with the said gears of the first-mentioned telescoping shafts to cause corresponding movement of said indicating 20 means with said inking rolls.

13. In a printing and recording machine of the character described, a stationary frame, a movable frame slidably mounted upon said stationary frame, and adapted to 25 have vertically reciprocatory movement therein, pivoted means for depressing said movable frame, printing rolls carried by said movable frame, levers carried by said movable frame and adapted to turn said 30 printing rolls, guide means for said levers provided with notches, handles for said levers, and spring pressed rods mounted in said handles having at one end a thumb engagement portion extending exterior of said 35 handle and provided at the other end with teeth adapted to engage said notches of said guide means and to be disengaged therefrom by pressure on said thumb engagement portion.

14. In a printing and recording machine of the character described, a stationary frame, a movable frame slidably mounted upon said stationary frame, and adapted to have vertically reciprocatory movement 45 therein, a pivoted frame connected to said vertically movable frame, printing rolls carried by said movable frame, levers carried by said movable frame, adapted to turn the said printing rolls, a master lever carried by said pivoted frame, adapted to be depressed to move said movable frame downwardly into printing position, guide means for said master lever provided with notches respectively in the upper and lower 50 ends thereof, a handle on said master lever, and a spring-pressed rod having at one end a thumb engagement portion and provided at the other end with a tooth adapted to engage and be disengaged from said notch 55 of said guide means by pressure on said thumb engagement portion.

15. In a printing and recording machine of the character described, a stationary frame, a movable frame slidably mounted 60 upon said stationary frame, and adapted to

have vertically reciprocatory movement therein, pivoted means for depressing said movable frame, printing rolls carried by said movable frame, levers carried by said movable frame, adapted to turn said printing rolls, stationary gears at each side of said printing rolls, rotatable plates at each side of said printing rolls, an inking roller mounted between said rotatable plates, provided at its ends with pinions engaging 70 said gears at each side of said printing rolls, and means connecting said rotatable plates with said stationary frame, said inking roller being at the printing portion of said printing rolls in the upper position of said movable frame, said rotatable plates adapted to be rotated by said connecting means upon downward movement of said movable frame, said roller adapted to be moved away from said printing portion by movement of said rotatable plates, said inking roller adapted to be turned by the engagement of said pinion with said gears.

16. In a printing and recording machine of the character described, a stationary frame, a movable frame slidably mounted upon said stationary frame, and adapted to have vertically reciprocatory movement therein, and pivoted means for depressing said movable frame, printing rolls carried 90 by said movable frame, a perforating comb carried by said movable frame, a shelf adapted to support a check to be printed and perforated, said shelf being provided with a plurality of openings beneath said perforating comb, said comb adapted to perforate said check by downward movement of said movable frame simultaneously with the printing of said check.

17. In a printing and recording machine 105 of the character described, a stationary frame, a movable frame slidably mounted upon said stationary frame, and adapted to have vertically reciprocatory movement therein and pivoted means for depressing 110 said movable frame, printing rolls carried by said movable frame, a perforating comb carried by said movable frame, a shelf adapted to support a check to be printed and perforated, said shelf being provided with a 115 plurality of openings beneath said perforating comb, said comb adapted to perforate said check by downward movement of said movable frame simultaneously with the printing of said check, and a waste receptacle carried by said shelf beneath said plurality of openings, adapted to receive the waste from the perforating of said check.

18. In a printing and recording machine, a stationary frame, a movable frame slidably 125 mounted upon said stationary frame, and adapted to have vertically reciprocatory movement therein, pivoted means for depressing said movable frame, a plurality of printing rolls carried by said movable frame, 130

5 levers carried by said movable frame adapted to turn one set of said movable rolls, gears connected to each of said rolls, and a plurality of racks extending over said plurality of printing rolls and engaging said gears, to cause corresponding movement of all the rolls by the movement of one.

19. In a printing and recording machine, a stationary frame, a movable frame slidably mounted upon said stationary frame, and adapted to have vertically reciprocatory movement therein, pivoted means for depressing said movable frame, a plurality of sets of printing rolls carried by said movable frame, levers carried by said movable frame, adapted to turn one set of said movable rolls, means connecting said rolls to cause corresponding movement of all the rolls by the movement of one, and a recording mechanism disposed beneath one of said sets of rolls, comprising a supply roller, a receiving roller, and a tape disposed between said rollers and carried beneath said set of printing rolls, a ratchet on said receiving roller, a lever, a pawl engaging said ratchet adapted to be operated by said lever, a trip lever connected to said first named lever, and means on said movable frame adapted to engage said trip lever during the reciprocatory movement of said movable frame to operate said lever mechanism to turn said receiving roller upon the upward movement of said movable frame.

20. In a printing and recording machine, a stationary frame, a movable frame slidably mounted upon said stationary frame, and adapted to have vertically reciprocatory movement therein, pivoted means for depressing said movable frame, a plurality of sets of printing rolls carried by said movable frame, levers carried by said movable frame, adapted to turn one set of said movable rolls, means connecting said rolls to cause corresponding movement of all the rolls by the movement of one, a recording mechanism disposed beneath one of said sets of rolls, comprising a supply roller, a receiving roller, and a tape disposed between said rollers and carried beneath said set of printing rolls, a ratchet on said receiving roller, a slotted lever, a pawl carried thereby and engaging said ratchet, a lever adjustably connected to said slotted lever, adapted to operate the same to move said ratchet, a trip lever connected to said adjustable lever, means on said movable frame adapted to engage said trip lever during the reciprocatory movement of said movable frame to turn said receiving roller upon the upward movement of said movable frame, said adjustable lever provided with means engaging the receiving roller, the increasing size of said receiving roller adapted to move said lever in said slotted lever for regulating the uniform movement of said tape.

21. In a printing and recording machine, a vertically movable frame, a stationary frame, means for depressing said movable frame, a plurality of sets of printing rolls carried by said movable frame, levers carried by said movable frame adapted to turn one set of said movable rolls, means connecting said rolls to cause corresponding movement of all the rolls by the movement of one, and a recording mechanism disposed beneath one of said sets of rolls, comprising a supply roller, a receiving roller, and a tape disposed between said rollers and carried beneath said set of printing rolls, a ratchet on said receiving roller, a slotted lever on said receiving roller provided with a pawl engaging said ratchet, a lever provided with a slot, a slide piece in said slot, a spring exerting a downward pull on said slide piece, a trip lever adapted to be moved by the upward and downward movement of said movable frame, and an arm connecting said trip lever with said slide piece, said ratchet adapted to be intermittently turned by the upward movement of said movable frame, and means carried by said slide piece engaging the upper surface of said receiving roller, said slide piece adapted to be moved upwardly in the said slot by the increasing size of said printing roll, to regulate the uniform movement of the tape.

22. In a printing and recording machine of the character described, a casing provided with a plurality of slots, a stationary frame, in said casing, a movable frame in said casing slidably mounted upon said stationary frame, and adapted to have vertically reciprocatory movement therein, pivoted means for depressing said movable frame, printing rolls carried by said movable frame, levers carried by said movable frame and adapted to turn said printing rolls, said levers extending through said slots of the casing, characters indicating amounts at the side of said slots, said levers adapted to be moved adjacent said characters to move said printing rolls into corresponding printing position, guide means for said levers provided with a plurality of notches corresponding to said characters, and a spring pressed tooth engaging said notches, to hold the said levers rigidly in position and means extending exterior of said handle adapted to operate said tooth.

23. In a printing and recording machine of the character described, a casing comprising a main section, and a type carrier section, a stationary frame within said main section, a slidable frame mounted to slide with respect to said stationary frame, a swinging arm extending exterior of said main section and adapted to impart a vertically reciprocatory movement to said slid- able frame, a plurality of printing rolls carried by said slidable frame and disposed

in said type carrier section, and levers carried by said slidable frame and extending exterior of said main section, adapted to turn said printing rolls.

- 5 24. A printing and recording machine of the character described, a casing comprising a main section, a type carrier section, and a printing shelf disposed beneath said type carrier section, a stationary frame, a slidable frame mounted to slide with respect to said stationary frame, a swinging frame pivoted at one end to said main section and engaging at its other end the said slidable frame, a lever arm carried by said swinging frame 10 and extending exterior of said main section
- 15

at the end thereof opposed to the pivot point of said swinging frame, a plurality of shafts carried by said swinging frame and projecting into said type carrier section, printing rolls carried by said shafts, and 20 levers carried by said sliding frame adapted to turn said shafts and said printing rolls, and extending exterior of said main section.

In testimony, that I claim the foregoing as my invention, I have signed my name in 25 presence of two subscribing witnesses.

AUGUST N. E. BOOS.
